UNITED STATES PATENT OFFICE

94,391

DESIGN FOR A MIRROR FRAME OR SIMILAR ARTICLE

Louis M. Piker, Hamilton, Ohio, assignor to The Hamilton Metal Products Company, Hamilton, Ohio, a corporation of Ohio

Application May 9, 1934, Serial No. 51,729

Term of patent 7 years

To all whom it may concern:

Be it known that I, Louis M. Piker, a citizen of the United States, residing at Hamilton, in the county of Butler and State of Ohio, have invented a new, original, and ornamental Design for a Mirror Frame or Similar Article, of which the following is a specification, reference being had to the accompanying drawing, forming part thereof:

Fig. 1 is a perspective view of the frame;
Fig. 2 is a front view thereof; and
Fig. 3 is an edge view of the same.

I claim:

The ornamental design for a mirror frame or similar article, substantially as shown.

LOUIS M. PIKER.
